UNITED STATES PATENT OFFICE

JOHN HOLTHE, OF STRATFORD, CONNECTICUT

CARTRIDGE

Application filed July 7, 1932. Serial No. 621,183.

This invention relates to cartridges, especially of the type used with small arms.

Heretofore, it has been customary to make the cartridge of two parts, one being a hollow drawn metal casing and the other being a projectile closing the front end of the shell or casing, the charge being located in the shell.

This form of cartridge is not only expensive to manufacture due to the many drawing and annealing operations required to produce the shell, but it also requires that provision be made and time be taken for ejecting the casing or shell after the shot has been fired.

It is one of the important objects of the present invention to provide ammunition in which the projectile is so formed as to constitute both the projectile and the casing or housing for the charge, and to provide means for closing the rear end of the projectile, which means is destroyed as a result of the firing of the arm. For this purpose, the projectile is made to have a substantial cavity for the charge, and a plug of celluloid or the like is provided to close its rear end.

Another important object of the present invention is to provide for decreasing the air resistance of the projectile and thus give it increased range and effectiveness. This is accomplished by the present invention by providing the projectile with an axial bore extending therethrough, so that air through which the projectile passes may be divided—a part going through the bore and the other part going around the exterior of the projectile in the form of slip-streams. In this way, formation of densified areas ahead of the bullet is avoided. Preferably, the axial bore of flares forwardly sharply from a point near its front end and from the same point flares gradually toward the rear end of the projectile at which the diameter of the bore is substantially the same as the outside of the projectile. In this way, the formation of pockets or vacuities behind the projectile which would tend to retard it in its flight is eliminated.

Such a hollow projectile could not, however, be discharged from a fire arm, and it is

necessary to plug the bore for at least the initial part of its flight.

It has been suggested heretofore to use more or less hollow projectiles, and in such cases it was proposed to close the axial bore or opening by a metal plug which was supposed to be ejected from the projectile at some point in its flight by the pressure of the air streams thereon. The work of ejecting this plug would, of course, retard the flight of the bullet.

Accordingly, an important feature of this invention is the provision of a plug for the hollow projectile which, of itself, becomes destroyed and is eliminated from the bore. This is accomplished in the preferred form of this invention by closing the forward end of the bore by means of a slow-burning material which is ignited by the main charge. If slow-burning gun powder or the like is employed for this purpose, the gases resulting from its combustion will expand in the rear end of the hollow projectile and be emitted from the open rear end thereof. These gases will, therefore, tend to fill any pockets which may tend to form at the rear of the projectile prior to the opening of the cavity. The slow-burning plug is prevented from being blown out through the front end of the projectile by being firmly compressed therein and because of the tapering bore in which it is compressed. The material of the slow-burning plug may be such as to generate gases or flames at such a rate that the emission of the latter from the rear end of the projectile serves to accelerate the latter, and thus increase its range or effectiveness.

In such fire-arms as machine guns, the rapidity with which the successive shots may be fired depends to some extent upon the time required to insert and eject the bullet. With the projectile and shell of the present invention, the ejecting operation is eliminated entirely. Accordingly, the rapidity with which the shots may be fired is materially increased.

In some cases, it is unimportant whether or not there is anything left to be ejected after the discharge, and in these cases the

rear end of the projectile may be formed of metal.

As a matter of fact, the hollow projectile of the present invention may be employed with a cartridge shell, particularly in cases where an extra heavy firing charge is required, or where a shorter projectile is desired. Even in such cases, an economy in the cost of producing the cartridge is effected, for some part of the charge may be carried in the hollow projectile, and the shell may accordingly be made shorter than would otherwise be required.

However, it is preferable to eliminate the use of the shell completely, for this is a costly part to make due to the fact that successive drawing and annealing operations are required in its fabrication.

Other features and advantages will hereinafter appear.

In the accompanying drawing—

Figure 1 is a plan view of the preferred form of the present invention.

Fig. 2 is a longitudinal sectional view of the cartridge shown in Fig. 1.

Fig. 3 is a sectional view of the projectile shown in Figs. 1 and 2, after it has been fired and while it is in the initial part of its flight.

Fig. 4 is a view similar to Fig. 3, but shows the projectile after the air passage plug has been burned out.

Fig. 5 is a plan view of the present invention applied to the standard cartridge shell.

Fig. 6 is a section of that form of the present invention shown in Fig. 5, and taken on line 6—6 in the latter figures.

Fig. 7 is a sectional view similar to Fig. 2, of a further modified form of the present invention.

With that form of the present invention shown in Figs. 1 to 4, there is provided a projectile 10 made of lead, copper, or any other suitable material, preferably slightly pointed as at 11 to more readily cut through

the air. Now, it should be particularly noted that this projectile is provided with an axial bore 12 therethrough, preferably conical in shape with its smallest diameter 13 near the front thereof and gradually tapering to a larger diameter near the rear thereof. This bore 12 at its front end is sealed with a plug 14 of slow burning powder; for example, a mixture of regular powder together with charcoal and clay which, upon drying, forms quite a solid plug and one which is adapted to remain in place and withstand a considerable pushing impact.

The part of the bore 12 between the rear end of the plug 14 and the rear end of the projectile 10 forms a chamber 15 for the reception of a properly proportioned main propelling explosive charge of gun powder, the grains of which are indicated at 16. This chamber 15 is sealed with a plug 17 of suitable material. Preferably, this plug or disk

17 is provided with a neck portion 18 adapted to be forced into a stepped portion 19 of the bore 12 to hold the disk in place and prevent the powder from release and loss. A flange 20 on the disk locates the disk in the stepped bore and limits its movement therein. A regular percussion or firing cap could be placed in this disk for engagement by a firing pin in the fire arm with which the cartridge is used. However, according to the present invention, the disk is provided with a small bore 21 and a deposit of fulminate 22 or other highly explosive material is deposited in the small bore and a cup 23 of suitable inflammable material is forced into the bore to form a weather and shock protective covering for the fulminate.

Use of this form in the present invention is as follows. The cartridge 10a formed by the present invention is placed in firing position in the fire-arm with which it is intended to be used. Now, when the user pulls the trigger, the firing pin impinges against the fulminate 22 to ignite the latter, and this in turn ignites the main supply of powder 16 to form highly compressed gases, which as they expand, eject the projectile 10 forwardly through the bore of the gun. These gases, because of the tapering bore 12 and because of the stop formed by the back of the plug 14, are concentrated near the axial center of the projectile and exert their maximum pushing force near the front of the projectile, preferably at about the center of gravity. This is a particularly important advantage with the projectile of the present invention for, by having the maximum pushing force near the axial center of the projectile, more accurate flight is assured—an advantage which is further enhanced by having the center of gravity of the projectile near the front thereof and especially by having the maximum pushing force of the explosive charge extend to a point near the center of gravity of the bullet.

When the main charge 16, which is preferably a highly explosive and quick burning powder, is fired, it ignites the plug 14 within the projectile 10 so that it burns and is consumed during flight of the projectile through the bore of the gun and during the initial part of its flight through free air. Preferably, the material of which this plug is made is so proportioned that it is certain to withstand the pushing impact of the main explosive charge. The tapered bore 12 facilitates this action, for, should the plug be forced forwardly in the bore 12 when the main charge 16 is exploded, the tapered bore serves to more tightly wedge the plug and prevent it from being forced out of the projectile. The plug 14 may be so made and proportioned as to burn out immediately after the projectile 10 has passed out of the gun, or it may be made to burn for a sufficiently long time to permit the general course of the projectile to be ob-

served. When the plug has burned out, there is formed a passage 12a through the center of the bullet for air which would normally retard it in its flight. This air passage prevents the building up of air pressure ahead of the projectile and avoids the formation of eddy currents and vacuums at its back end. The composition forming this plug is preferably such that it forms additional highly 10 expandible gases to fill the bore in the gun and accelerate the bullet on its flight therethrough, and to increase the original impetus given by the main firing charge. Besides, after the projectile has left the gun, the gases 15 formed by the burning of the material of the plug tend to fill any vacuum which might tend to form behind the projectile while the passage 12a is closed, and may be made to act in the nature of a rocket to give further 20 propelling power to the projectile.

The plug or disk 17, according to the present invention, may be made of a highly combustible material such as celluloid and the like, and is arranged to remain substantially 25 whole during the firing of the main charge 16 and to quickly consume itself by fire immediately thereafter.

As has been indicated, the projectile 10 may 30 form the main body of the cartridge of this invention, and it in turn is projected from the bore in the gun in the form of a bullet. With the self-consuming disk 17, there is no scrap shell or any other mechanical residue after the cartridge has been fired. After firing 35 a cartridge of the present invention, it is merely necessary to automatically or manually drop another cartridge of the same form in the cartridge chamber of the gun and fire it. With it there is nothing to eject from 40 the gun, and in automatic fire-arms the shots per minute may be materially increased by its use. Moreover, the cost of providing shells is eliminated. Yet, the projectile may contain sufficient mass to do the work for which 45 it is intended, and it may carry a sufficiently large powder charge for its purpose.

It should be particularly noted that the air-passage 12a gradually expands from near the front toward the rear end of the projectile 10, 50 so that the air rushing therethrough may expand and be passed almost to the outer periphery of the projectile, thereby reducing to a minimum any possibility of the formation 55 of a vacuum or eddy currents at the rear of the bullet, which would tend to retard it in its flight. This relatively large diameter of the bore at this point and consequently thin shell for the base of the projectile is made possible according to the present invention 60 by having it so constructed that the main force of the explosive charge 16 is transmitted toward the axial centre of the bullet and near the front end thereof where the walls are relatively thick.

65 Preferably the bore 12 is provided with a

section 24 at the front end of the projectile which flares sharply and serves to direct a larger volume of the nose resistant air through the projectile and provide a larger volume to fill the vacuum at the back end of the projectile while it is in flight. 70

A further advantage of reducing the vacuum at the rear of the bullet to a minimum is reduction in the turbulence of the projectile while in flight and a consequent reduction in the possibility of tumbling. 75

In Figs. 5 and 6 there is shown a modified form of the present invention wherein the projectile of the present invention is shown as applied to a cartridge shell 25. The projectile 10 and plug 14 shown with the preferred form of the present invention may be used in this form of the invention; or they may be used with substantial modification if desired. However, when a shell is employed as in Figs. 5 and 6 the main charge 16a of powder is placed within both the shell 25 and the projectile 10, the latter being forced into a neck 26 of the shell, and keeping the powder in place. This form of cartridge is especially suited for long range shooting, because a large supply of main powder charge 16a may be stored therein and in the projectile bore 12 without increasing the length of the cartridge. 80 85 90 95

This cartridge is placed into the firing chamber portion of the gun with which it is intended to be used and when the gun is manipulated the firing pin engages a usual or suitable firing cap 27 in the shell to ignite the main charge 16a, and the gases formed thereby push against the back end of the plug 14 to push the projectile free from the neck 26 and speed it through the bore of the gun. The plug 14 is ignited by the main charge 16a and burns out during the initial part of the flight of the projectile to provide a free passage for the air in the same manner as in the form of the invention illustrated in Figs. 1 to 4. 100 105 110

In Fig. 7 there is shown a modification of the form of cartridge shown in Figs. 1 to 4 inclusive. It may in all respects be like the latter except for a different form of rear plug or base 17a which is made of metal or some other material which is not inflammable. This disk 17a is provided with a neck portion 27 adapted to be forced into the stepped bore 19 of the projectile 10 to seal the main powder charge 16 between it and the 14 of slow burning powder. The disk is also provided with a flange 28 to limit movement of the disk into the projectile and to locate the cartridge in the firing chamber. A usual or suitable firing cap 29 is located in the disk for the purpose of igniting the main charge 16. 115 120 125

The present invention has been described as embodied in a cartridge for use in small fire arms, however, it will be readily appreciated 130

that it may also be embodied in larger guns to advantage.

Other variations and modifications may be made within the scope of this invention and 5 portions may be used without others.

Having thus described the invention what I claim as new and for which I desire to obtain Letters Patent, is:

1. A cartridge comprising a projectile having a bore extending axially therethrough; a plug of slow burning material closing the front end of the bore; an explosive charge within said bore; a metal plug in the rear end of the bore forming a seal for the explosive charge.

2. A cartridge comprising a projectile having a bore extending axially therethrough; a plug of slow burning material near the front end of the bore; an explosive charge 20 within said bore; and a celluloid plug forming a seal for the explosive charge; adapted to be destroyed by the explosive charge within the bore of the gun with which the cartridge is used and to make unnecessary the removal of any cartridge scrap before placing 25 another cartridge in firing position.

3. A cartridge comprising a projectile having a bore extending axially therethrough; a plug of slow burning material near the 30 front end of said bore, and adapted to burn out during the initial part of the flight of the projectile; an explosive charge within said bore; and a plug of slow burning material in the other end of said bore serving 35 to seal the high explosive charge within the bore.

4. A projectile having a tapering bore extending axially therethrough; and a plug of slow burning material adapted to burn 40 out during the initial part of the flight of the projectile, said plug being tapered substantially like the tapered bore so as to wedge tighter therein when subjected to the pushing impact of an explosive flight impelling 45 charge.

5. A projectile having a long bore extending axially therethrough and flaring from near the front toward the rear where it has substantially the same diameter as the 50 outside of the projectile; an explosive charge within said bore; and a plug of relatively slow burning material ignited by the main explosive charge and adapted to burn out during the initial part of the flight of the 55 bullet to open up the bore and form an air passage through the projectile.

6. A projectile having a long bore extending axially therethrough and flaring from near the front toward the rear where it has 60 substantially the same diameter as the outside of the projectile; an explosive charge within said bore; and a plug of relatively slow burning material ignited by the main explosive charge and adapted to burn out 65 during the initial part of the flight of the

bullet to open up the bore and form an air passage through the projectile, said plug being made of gas forming material which while burning ejects from the rear open end of the projectile a gas which prevents the formation of a flight retarding vacuity in back of the projectile.

7. A projectile having a long bore extending axially therethrough and flaring from near the front toward the rear where it has substantially the same diameter as the outside of the projectile; an explosive charge within said bore; and a plug of relatively slow burning material ignited by the main explosive charge and adapted to burn out during the 70 initial part of the flight of the bullet to open up the bore and form an air passage through the projectile, said plug being made of gas forming material which while burning ejects from the rear open end of the projectile a gas which prevents the formation of a flight retarding vacuity in back of the projectile, the expulsion of said gas from the rear end of the projectile serving to drive the projectile forwardly.

8. A projectile having a bore extending axially therethrough, said bore flaring toward the rear to substantially the same diameter as the outside of the projectile and serving to diffuse the air, which passes through the bore, at the back of the bullet to a point which prevents the regular air currents which sweep over the bullet from forming a flight restraining air pocket in back of the projectile during its flight, and a self-destroying plug closing the bore adjacent the front end thereof during the initial part of the flight of the projectile.

Signed at Bridgeport, in the county of Fairfield, and State of Connecticut, this 105 5th day of July, 1932.

JOHN HOLTHE.
